CONTROL MEANS FOR BOOKKEEPING
MACHINES

Walter A. Anderson, Rockford, Ill., assignor, by
mesne assignments, to Underwood Elliott
Fisher Company, New York, N. Y., a corpora-
tion of Delaware

Application January 6, 1933, Serial No. 650,393

1 Claim. (Cl. 235—58)

This invention relates to bookkeeping and similar machines having a laterally movable paper carriage together with means whereby the carriage is enabled to control the printing, computing 5 and other mechanisms of the machine. Such a machine is disclosed in the Sundstrand application Serial No. 118,628 filed June 26, 1926 (which corresponds to French Patent No. 625,678). The carriage is equipped with a control plate adapted 10 to coact with control devices located on the stationary framework of the machine. The control plate is removable from the carriage so that another control plate adapted to effect a different succession of operations may be substituted. The 15 means whereby the control plate is detachably connected to the carriage is of such a nature that the plate must be engaged with or disengaged from the carriage by imparting several different kinds of movements to the plate. Unless these movements are properly performed, difficulty will be 20 encountered in attaching or detaching the plate and if care be not used damage may be done to adjacent control elements. Experience has shown that some users of the machine are not 25 sufficiently adept or careful in attaching and detaching the control plate.

The object of the present invention is to improve upon the construction shown in the above-mentioned Sundstrand application with a view 30 to simplifying the operation of attaching or detaching the control plate and reducing the possibility of injury to other parts.

In the accompanying drawing Figure 1 is a right-hand end elevation of a paper carriage equipped with my improvements.

Fig. 2 is a fragmental plan view of the control plate.

Fig. 3 is a section on line 3—3 of Fig. 2.

Fig. 4 is a fragmental plan view.

Fig. 5 is a perspective view of the control plate and the pivot shaft to which it is attachable.

Fig. 6 is a section on line 6—6 of Fig. 2.

In the drawing, 1 denotes a paper carriage mounted on a track member 2 by means of roller bearings 3. 4 is a group of control elements located on the machine frame and connected to various mechanisms of the machine. 5 is an elongated control plate attached to the carriage in position to travel directly above the control elements 4 and having stop pins 5a permanently secured thereto in positions to coact with the control elements 4. Said plate is attached to the carriage through the medium of a pivot shaft 6 having end journals 7 which are mounted in bearings in the carriage. The shaft 6 has a flat upper

side 8 upon which one edge portion of the plate 5 is adapted to lie, as shown in Fig. 3. The means for securing the plate 5 to the shaft 6 comprises two pins 9 affixed to the shaft in position to project through openings 10 formed in the forward 5 edge portion of the plate near the ends thereof. Several spring-actuated latching studs 11 are mounted on the shaft 6. In the construction selected for illustration herein, there are three such studs between the pins 9 and a fourth stud be- 10 yond or at the outer side of the right-hand pin 9. In the present instance all of these latching studs are alike. Each comprises a head 12 and a stem 13, the latter being slidable in an opening 14 in the shaft 6. A compression spring 15 located in a re- 15 cess 16 in the shaft bears at one end against the end wall of the recess and at its other end against a flange on the stem 13. A washer 17 surrounds the stem 13 above the shaft 6. As shown in Fig. 3, the washer 17 is of somewhat less thickness than 20 the control plate. The lower side of the head 12 is made tapering toward the stem, as at 18. The forward edge of the plate has notches 19 therein to afford clearance for the studs 11.

On the plate 5 is a locking slide 20 to coact with 25 the studs 11 in securing the plate to the shaft 6. Said slide is held to the plate 5 by means of two headed studs 21 fixed in the plate and extending through elongated openings 22 in the slide. A similar opening 23 in the slide provides clearance 30 for the right-hand pin 9, as shown in Fig. 6. Openings 24 are formed in the slide to afford clearance for the heads 12 of the studs 11 as the control plate is being laid on the pivot shaft 6, as in Fig. 4. Communicating with each opening 24 35 is a relatively narrow elongated opening 25 which may be moved into register with the stem 14 by longitudinal movement of the slide. The walls of the opening 25 are slightly chamfered as shown at 26 in Fig. 2 to coact with the beveled lower side of 40 the head 12 and thus cam up the head 12 as the stem 13 enters the narrow slot 25. The inner end of the slot 25 is slightly enlarged as at 28 to receive the lower portion of the tapered surface 18 of the stud 11. 45

The slide 20 is longitudinally movable to bring the openings 25a into and out of register with the studs 11 by any preferred means, as for example, a lever 27 pivoted to the control plate at 28 and having a finger-piece 29. Said lever is connected 50 to the slide 20 through the medium of a link 30.

In practice, the selected control plate is laid on the flat upper side of the pivot shaft 6 with the pins 9 extending through the openings 10 and the latching studs 11 projecting through the openings 55

24. The lever 27 is then swung forward, thereby drawing the slide 28 toward the right as viewed from the front of the machine, and thus bringing the relatively small openings 25^a below the heads 12 of the studs 11. Such movement of the slide cams the heads 12 up slightly so as to cause the heads to bear with some pressure upon the slide 28, thus holding the control plate firmly to its pivot shaft and preventing rattling. When the control plate is to be removed preparatory to the substitution of a control plate having a different arrangement of stop pins 5^a, the order of operations just described is performed in reverse order.

10 It will be seen that the heads 12 cannot leave the openings 25^a without rising slightly, whereby a 15 detent action is obtained which serves to hold the slide 28 in locking position.

15 It will be evident that the control plate is placed 20 in position on the pivot shaft, or removed therefrom, by a simple vertical movement which requires a minimum of care on the part of the operator, and which obviates the danger of damage to adjacent parts.

I would have it understood that various changes

may be made without departing from the spirit and scope of the invention as set forth in the appended claim.

I claim as my invention:

5 In a bookkeeping machine, the combination of a plate, a part to which said plate is detachably secured, and means for thus securing the plate to said part comprising two pins on said part to enter holes in the end portions of the plate, a series of headed studs on said part, spring means 10 urging the heads of said studs toward said part, the sides of said heads adjacent said part being beveled, said plate having openings affording clearance for said heads, a slide secured to the plate for limited longitudinal movement, said slide having openings providing clearance for said heads, and each of the last-mentioned openings communicating with a narrow opening adapted, on movement of the slide, to register with said studs below the heads thereof, said spring means acting 15 to press the slide against the plate and the plate against said part to prevent rattling, and lever means for moving the slide.

WALTER A. ANDERSON.
